(57) **CLAIM**

The ornamental design for a mobile device with an animated graphical user interface, as shown and described.

DESCRIPTION

FIG. 1 is a front view of a first image of a first embodiment of a mobile device with an animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a first image of a second embodiment of a mobile device with an animated graphical user interface showing our new design;

FIG. 8 is a front view of a second image thereof;

FIG. 9 is a front view of a third image thereof;

FIG. 10 is a front view of a fourth image thereof;

FIG. 11 is a front view of a fifth image thereof;

FIG. 12 is a front view of a sixth image thereof;

FIG. 13 is a front view of a first image of a third embodiment of a mobile device with an animated graphical user interface showing our new design;

FIG. 14 is a front view of a second image thereof;

FIG. 15 is a front view of a third image thereof;

FIG. 16 is a front view of a fourth image thereof;

FIG. 17 is a front view of a fifth image thereof;

FIG. 18 is a front view of a sixth image thereof;

FIG. 19 is a front view of a first image of a fourth embodiment of a mobile device with an animated graphical user interface showing our new design;

FIG. 20 is a front view of a second image thereof;

FIG. 21 is a front view of a third image thereof;

FIG. 22 is a front view of a fourth image thereof;

FIG. 23 is a front view of a fifth image thereof; and,

FIG. 24 is a front view of a sixth image thereof.

(Continued)

The first through the fourth embodiments comprise a mobile device having an animated graphical user interface. In the first embodiment, the appearance of the transitional image sequentially transitions between the images shown in FIGS. 1 through 6. In the second embodiment, the appearance of the transitional image sequentially transitions between the images shown in FIGS. 7 through 12. In the third embodiment, the appearance of the transitional image sequentially transitions between the images shown in FIGS. 13 through 18. In the fourth embodiment, the appearance of the transitional image sequentially transitions between the images shown in FIGS. 19 through 24. The process or period in which one image transitions to another image forms no part of the claimed design.

The dash-dot lines in each figure and the area between the inner dash-dot line and the outer dash-dot line in each figure form no part of the claimed design. The area within the inner dash dot line in each figure is part of the claimed design.
